REFUSE COLLECTION VEHICLE

John W. Knight, Sr., New Hampton, Iowa, assignor to Sani-Systems, Inc., New Hampton, Iowa

Filed Mar. 30, 1970, Ser. No. 22,103

Term of patent 14 years

Int. Cl. D12—09

U.S. Cl. D14—3

Fig. 1

Fig. 2

Fig. 3

Fig. 4

FIG. 1 is a side elevational view of a refuse collection vehicle showing my new design;

FIG. 2 is a top plan view thereof;

FIG. 3 is an end view as seen from the left of FIG. 1; and

FIG. 4 is an end view as seen from the right of FIG. 1.

The side opposite to that shown in FIG. 1 is a mirror image thereof.

I claim:

The ornamental design of a refuse collection vehicle, substantially as shown and described.
